HANDKERCHIEF HOLDER
 Paul B. Stephens, Chicago, Ill.
 (731 Mill St., Mount Vernon, Ind.)
 Filed July 18, 1962, Ser. No. 210,662
 5 Claims. (Cl. 2—279)

This invention relates to an improved handkerchief holder, and particularly a holder adapted to hold a full size handkerchief in proper position in the upper pocket of men's suit coats, waitresses' uniforms, and other garments while the handkerchief is folded into the particular shape desired by the wearer.

In garments such as suit coats, waitresses' uniforms, and the like, a breast pocket is provided. Frequently, a handkerchief is folded neatly and inserted in the pocket in a preselected position for embellishing the garment according to the aesthetic tastes of the wearer. When the handkerchief is fresh and newly inserted, it serves the intended purpose, but due to the movement of the garment occasioned by changes in posture of the wearer, the handkerchief shifts from its original position and becomes unattractively misaligned with the pocket. It must be rearranged repeatedly or it not only does not embellish the garment, but actually detracts from its appearance, with resultant implications of a proclivity toward untidiness of the wearer.

Heretofore, holders have been provided to which handkerchiefs may be connected and the combination inserted into the pocket for the purpose of retaining the handkerchief more nearly in the desired position throughout the period of use. However, there are several objections to the prior holders. The most general objection is that they add bulk which mis-shapes the garment or forms pressure lines therein. Also, they are limited in length and are fixed in position relative to the handkerchief so that the handkerchief cannot be adjusted relative to the holder while the holder with the handkerchief installed is in the pocket. Instead, the combination must be repeatedly withdrawn, the handkerchief and holder adjusted relative to each other, and reinserted in the pocket until the desired position of the handkerchief is obtained. In other holders, no adjustment of the handkerchief lengthwise of the holder can be made due to the fastening means provided.

Again, particularly in men's suits, the upper entrance portion of the pocket is narrower for a distance of from a half inch to an inch below the upper edge of the pocket than the portion of the pocket therebelow. Consequently, the prior holders, which are of uniform width, do not fit the pocket properly for holding the handkerchief in place.

In accordance with the present invention, a relatively simple holder is provided which is arranged to retain its position in the pocket even though the general width of the pocket is wider than the entrance portion. The holder is arranged to hold a handkerchief in different preselected positions of the handkerchief lengthwise of the holder. It is made to yieldably grip the handkerchief so that the handkerchief can be adjusted readily to the desired height after the holder and handkerchief combination are in a pocket simply by holding down the holder with the thumb and working the handkerchief up or down relative thereto with the fingers into the adjusted position desired. The holder has an advantage in that the amount of tension or resistance to movement of the handkerchief lengthwise of the holder, which is lengthwise of the pocket, can be adjusted readily.

Various other objects and advantages of the invention will become apparent from the following description wherein reference is made to the drawings, in which:

2

FIG. 1 is a front elevation of the holder of the present invention with a handkerchief installed thereon, and the combination in position in the breast pocket of a man's coat, a fragment of the coat and the pocket being shown in section for clearness in illustration;

FIG. 2 is a right end elevation of the handkerchief and holder shown in FIG. 1, the pocket being omitted for clearness in illustration;

FIG. 3 is a front elevation of the holder;

FIG. 4 is a rear elevation of the holder;

FIG. 5 is a vertical sectional view of the holder taken on the line 5—5 of FIG. 3;

FIG. 6 is a horizontal cross sectional view taken on the line 6—6 of FIG. 3; and

FIG. 7 is a rear elevation of the holder, similar to FIG. 4, showing the holding means for the handkerchief adjusted for tension.

Referring to the drawings, the holder and handkerchief combination is shown in FIG. 1 installed in a breast pocket 1 such as is customary in men's coats. Generally, such pockets have a relatively narrow entrance portion 2 at their upper end, this portion extending from about one-half to one inch from the upper edge 3 of the pocket. The inner lining is sewed on a bias, as indicated at 4, so as to slope downwardly and outwardly from the lower end of the entrance portion until it merges with the adjacent side of the wider lower portion of the pocket 5. The pocket is of the normal depth and has a bottom, as indicated at 6. In order to hold a handkerchief 7 neatly folded and in proper position in the pocket 1, a holder 9 embodying the present invention is provided.

The holder is in the form of a card 10 of self supporting and somewhat stiff but resilient sheet material, such as a thin sheet of synthetic organic plastic, celluloid, and the like. The card 10 preferably is approximately rectangular in outline except that it is provided with lateral ears 11 which are coplanar with the sheet and extend outwardly from the lateral edges of the card a fraction of an inch; for example, one half inch.

The card has a shortened upper portion 12 which is above the upper edge of the ears 11, the lower limit of which is indicated by the line x—x. It has a longer lower portion 13 below the lower edge of the ears 11, the upper boundary of which is indicated by the line y—y. The card has a central portion 14 which lies between the lines x—x and y—y. Generally, the upper portion 12 is such that it extends from the lower end near to the upper end of the entrance portion 2 of the pocket while the upper edges of the ears 11 lie just beneath the lower end of the entrance portion where the inner lining is biased, as at 4. The lower portion 13 of the card is sufficiently long to extend close to the bottom of a conventional pocket. The ears have trim lines 15 so that they can be readily cut to the width required for the particular pocket. Likewise, the lower portion 13 has trim lines 16 so that it can be cut to the desired height by trimming off part of the material. Thus, the card can fit into pockets of different widths and depths throughout a wide range of pocket sizes which are customary on garments from waitresses' uniforms to men's suit coats.

The handkerchief, after being folded to the shape desired, is mounted detachably on the front face of the card 10 with its upper edge standing above the upper edge of the card portion 12 approximately the amount that the handkerchief is to extend out of the pocket. In order to hold the handkerchief adjustably on the front face of the card, rubber bands 17 and 18 extend transversely of the card and are spaced from each other lengthwise of the card, and completely encircle the card. This is so that they do not buckle the relatively thin sheet material of which the card is composed when they hold the handkerchief sufficiently snugly against the face

70

of the card so that it remains in position endwise relative to the card under normal wearing conditions. For this purpose, the band 17 is arranged with its front portion 17a extending across the front face at the edges of the ears adjacent their juncture with the portion 12, and thus lie along line x—x. Correspondingly, at the front face, band 18 is arranged with its front portion 18a extending along line y—y. Generally, the bands extend parallel to the upper and lower edges of the card. At the rear of the card, however, the bands slope away from the respective end portions 12 and 13 toward the transverse center of the card, as indicated at 17b and 18b. They have rear portions 17c and 18c which are between their bias portions and lie in face to face relation to the rear face of the card. At their inner ends, the portions 17b and 18b are engaged by suitable tongues 19. This assures that the portions 17a and 18a do not creep away from the ears toward the ends of the card nearest to them. The tongues 19 are located transversely of the card near the ears, and are cut out of the sheet material of the card and joined to it at the bases 20. They extend away from their bases longitudinally of the card toward the longitudinal midportion of the central portion 14.

The tongues 19 are of substantial width at their bases 19a or junctures with the card and operable to pinch the rubber bands 17 and 18 at their points of engagement therewith. This pinching action is such that the portions 17a and 18a of the bands can be stretched and drawn relatively tightly against the handkerchief for exerting greater pressure thereon, the excess length and looseness resulting being accumulated in the portions 17c and 18c between the tongues, thus regulating the pressure with which the handkerchief is held pressed against the front face of the card. Due to the position of the tongues relative to the upper and lower edges of the ears, the portions 17b and 18b pull the ends of the portions 17a and 18a toward the portion 14 of the card and thereby hold the portions 17a and 18a firmly at the juncture of the ears with the edges of the portions 12 and 13. These junctures thus provide restraining shoulders for preventing the portions 17a and 18a of the rubber band from movement toward each other endwise of the card.

With this arrangement, the handkerchief, folded as desired, may be placed on the forward face and the portions 17a and 18a of the band adjusted to the desired stretch or tension. Any slack is taken out at the portions 17c and 18c between the tongues. With the handkerchief thus held against the face of the card, if the garment movement urges the handkerchief to move it toward either end of the card, the band portions 17a and 18a and 17b and 18b stretch and move resiliently until the external force is relieved, whereupon the bands pull the handkerchief back to its original position. However, with increase force as deliberately applied by the fingers of the wearer, the handkerchief can be pulled sufficiently hard so that it slips beneath the bands, thus affording adjustment endwise relative to the card.

In operation, with the folded handkerchief resiliently pressed against the forward face of the card in the approximate position desired, the tension band portions 17a and 18a are properly adjusted. The assemblage of card and handkerchief is slid into the pocket with the handkerchief forward, the card being bowed transversely to permit the ears 11 to pass below the bottom of the entrance portion 2 of the pocket. The card is then released and is in proper position in the pocket due to the engagement of the ears with the edges of the pocket near the inner end of the entrance portion 2. The card retains its upright position. In this position, the wearer can adjust the handkerchief by holding down on the upper edge of the holder with his thumb and working the handkerchief to the desired position with his fingers. This is a very simple operation and enables him to see

the position of the handkerchief during the manipulation.

Regardless of the adjusted position of the handkerchief lengthwise along the card, it will remain in the proper position relative thereto and be retained in proper position relative to the pocket.

The holder can be used with any type of handkerchief. If desired, the handkerchief may be installed on the card by leaving it partially unfolded and passing the lower end around to the back of the card and beneath the bands at the back, or it may be left loose at the back, depending upon the pocket to hold it in place.

In view of the position of the tongues, the bands are always held so that the portions 17a and 18a remain in place. If the handkerchief is pulled upwardly by movement of the garment without movement of the handkerchief relative to the portions 17a and 18a, but by flexure and stretching thereof, the portions 17a and 18a permit the handkerchief to move slightly under stresses imposed by the movement of the garment, but restore it to its original position as the garment resumes its position.

On the other hand, by applying sufficient force on the handkerchief with the fingers, while holding the card with the thumb, the handkerchief can be made to slip relative to the portions 17a and 18a and thus can be adjusted to the position desired while the assembly is in the pocket and readily observable.

It is found that in the operation two bands are essential for proper holding and maintenance of the handkerchief in alignment with the card. Further, in substantially all cases the wide ears are desirable and necessary. Again the adjustment afforded by the pinching of the rubber bands by the tongues at the rear face of the holder afford an adjustment so that the holder can accommodate itself to the thicknesses of different handkerchiefs, depending upon the particular fold desired by the wearer and the material of which the handkerchief is composed.

Having thus described my invention, I claim:

1. A holder for handkerchiefs and comprising a card of relatively thin self supporting sheet material of generally rectangular outline, said card having a front face, a rear face, an upper portion, a midportion, and a lower portion, lateral edges extending from one end of the card to the other, the midportion of the sheet being wider than the upper and lower portions and providing ears having upper lateral edges joining with the lateral edges of the upper portion at an abrupt angle and with lower lateral edges joining the lateral edges of the lower portion at an abrupt angle, said card having at its rear face upper tongues and lower tongues, said upper tongues having their junctures with the card spaced downwardly from the junctures of said upper lateral edges with the edges of the upper portion, and said upper tongues extending from their junctures downwardly, said lower tongues having their junctures with the card spaced upwardly from the junctures of said lower lateral edges with the lateral edges of the lower portion, and said lower tongues extending upwardly from their junctures, upper and lower rubber bands encircling the card, the upper band extending straight across the card at the front face of the card at the junctures of the upper edges of the ears with the upper portion of the card, respectively, the lower band extending straight across the card at the front face of the card at the juncture of the lower edges of the ears with the edges of the lower portion of the card, respectively, the upper band at the rear face of the card sloping from the upper portion downwardly and inwardly transversely of the card and passing between the rear face of the card and the upper tongues, the lower band at the rear face of the card sloping from the lower portion upwardly and inwardly transversely of the card and passing between the rear face of the card and the lower tongues, and each band being pinched be-

tween its associated tongues and the card at the juncture of its associated tongues and card.

2. A holder according to claim 1 wherein said tongues are resilient and normally resist movement away from the plane of the card, whereby each rubber band can be tensioned between the tongue and the card at the juncture of its associated tongues with the card and held with the tension of the bands at one face of the card different from the tension of that portion of the band which extends between its two associated tongues.

3. A holder according to claim 2 wherein the tongues of each set are spaced apart so that the outermost tongues are nearer the lateral edges of the sheet than the lateral mid-portion of the sheet.

4. A holder for a handkerchief and comprising a card of relatively thin, self-supporting, sheet material of generally rectangular outline and having a front face and a rear face, a set of upper restraining shoulders spaced from each other transversely of the card, a set of lower restraining shoulders spaced from each other transversely of the card and spaced from the upper restraining shoulders endwise of the card, first tongue means on the rear face of the card and joined to the card at a location spaced in one direction endwise of the card from the upper restraining shoulders, said first tongue means extending from said location endwise of the card in a direction away from the upper shoulders, second tongue means on the rear face of the card and joined to the card at a location spaced in a direction endwise of the card from the lower restraining shoulders, said second tongue means extending endwise of the card in a direction away from the lower shoulders, rubber bands extend-

5 ing transversely of the card and encircling the card, one of the bands engaging the upper shoulders and passing between the rear face of the card and the first tongue means and another of the bands engaging the lower shoulders and passing between the rear face of the card and the second tongue means, the upper restraining shoulders facing in a direction away from the direction in which the first tongue means extends and the lower restraining shoulders facing in a direction away from the direction in which the second tongue means extends.

10 5. A holder according to claim 4, wherein each tongue means comprises at least two laterally resilient tongues which normally resist movement rearwardly in a direction away from the plane of the card so that each 15 rubber band can be pinched between the rear face of the card and its associated tongues at the juncture of its associated tongues with the card and the portion of the band at the front of the card is maintained under tension independently of the condition of the portion of the 20 band which extends between its associated tongues.
